US00D983152S

(12) **United States Design Patent** (10) **Patent No.:** **US D983,152 S**
Mai (45) **Date of Patent:** **** Apr. 11, 2023**

(54) **MICROPHONE**

(71) Applicant: **Shenzhen Xunweijia Technology Development Co., Ltd.**, Shenzhen (CN)
(72) Inventor: **Qibin Mai**, Gaoyao (CN)
(73) Assignee: **Shenzhen Xunweijia Technology Development Co., Ltd.**, Shenzhen (CN)
(**) Term: **15 Years**
(21) Appl. No.: **29/841,892**
(22) Filed: **Jun. 9, 2022**
(51) **LOC (14) Cl.** **14-03**
(52) **U.S. Cl.**
USPC **D14/125**

CLAIM

The ornamental design for a microphone, as shown and described.

DESCRIPTION

FIG. 1 is a front perspective view of a microphone, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view thereof;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines in the drawings illustrate the portions of the microphone, which form no part of the claimed design.

1 Claim, 14 Drawing Sheets
